UNITED STATES PATENT OFFICE.

THOMAS V. ALLIS, OF BRIDGEPORT, CONNECTICUT.

SYSTEM FOR CONTINUOUS METAL-ROLLING.

SPECIFICATION forming part of Letters Patent No. 673,791, dated May 7, 1901.

Application filed October 4, 1900. Serial No. 31,989. (No model.)

To all whom it may concern:

Be it known that I, THOMAS V. ALLIS, a citizen of the United States, and a resident of Bridgeport, in the county of Fairfield and 5 State of Connecticut, have invented certain new and useful Improvements in Systems for Continuous Metal-Rolling, of which the following is a specification.

My invention is an improved system for 10 continuous metal-rolling, and is to be fully set forth in the following specification.

To enable others to understand my invention, reference is had to the accompanying drawings, in which—

15 Figure 1 represents a plan of a portion of my improvement, consisting of a continuous track with a train of furnaces mounted thereon and coupled together and to a truck adapted to carry propelling mechanism and a 20 double-chambered tank for air and gas, a centrally-located column and pipes for conveying gas and air to said tank, a turn-table let into the main track for the purpose of switching off any furnace of the train needing 25 repairs, also a plan view of a rolling-mill adjacent to the line of travel of the furnaces. Fig. 2 is an enlarged side elevation of two of the furnaces coupled together and to the propelling-truck, all mounted on a section of the 30 track. Fig. 3 is an enlarged detail view showing a sectional view of the throat of a furnace having a lug depending therefrom and engaged with a depressible stop adapted to be located in the path of the furnaces. Fig. 35 4 is an enlarged end elevation of the propelling-truck, showing a part of the driving mechanism, also a view of the gas and air tank. Fig. 5 is a modified form of the main track, which is laid in a complete circle. Fig. 40 6 is a central sectional view of a furnace preferably adapted to be used on a circular or continuous track, also means consisting of a pivoted feeding-chute for expediting the charging of the furnaces and a charging 45 bench or table in close proximity to said chutes. Fig. 7 is an upper plan view of the furnace, chute, and table shown at Fig. 6. Fig. 8 is a view of the gas and air conducting column adapted to be located at the center of 50 the circularly-constructed track and a broken view of the gas and air pipes leading there-

from to the tank mounted on the propelling-truck.

The construction and operation are as follows:

1, Fig. 1, is a circular or approximately circular track, which may be of any dimensions required. It may be fifty or one hundred feet in diameter, more or less, the object being to mount a sufficient number of 60 furnaces thereon so that there will be a constant delivery of heated metal from the furnaces to the reduction-rolls, with the exception, of course, of the fraction of time necessary to bring each consecutive furnace to the 65 rolls after the one preceding it has been discharged of its contents. The track shown at Fig. 1 has the straight run 1^a, in order that the throats 3 of the furnaces may be brought parallel with the guide 4, located close to the 70 rolls 5. The furnaces are coupled together by the bars 7 and 8 and pin 6. The truck 9 carries the tank 10, divided into two vertical compartments adapted to receive gas and air 75 in the manner presently to be more fully described. The mechanism shown for propelling the truck is constructed as follows:

11, Fig. 4, is the front axle of the truck. 12 is a large worm-gear loosely mounted thereon and having a cone-seat on one side 80 to be engaged by the cone 13, adjustably splined to the axle. 14 represents nuts engaging the threaded portion 14^a of the axle, whereby the frictional adjustment of the cone with the gear is effected. 15 is a worm mounted on the shaft 16 for driving said gear. The mechanism for driving this shaft is not shown, as any suitable device—such, for instance, as an engine mounted on the truck or an electric motor—can be employed. It will also be 85 understood that other mechanism besides the worm-gear and friction-cone may be used.

17 and 17^a represent gas and air tubes in short sections, with each furnace carrying its own. These sections are detachably connected by the couplings 18 and 18^a. The branches supplying the burners and leading from each of these sections into the several furnaces are not shown; but they are supposed to enter at the bottom of the furnaces, 90 although they can be otherwise arranged, if desired.

In operating my system the furnaces are brought to the proper temperature for heating the metal to be rolled. The train of furnaces is then moved over the track until the 5 lug 3^a of one of the furnaces, Fig. 3, depending from the under side of the throat 3 of each furnace, is brought in contact with the stop 19, depressibly mounted in the base 20. This will offer sufficient resistance to cause 10 the worm-gear 12, Fig. 4, to slip, which will notify the operator mounted on the truck, who will immediately stop the propelling mechanism. The location of the stop 19 and lug 3^a is such that when they engage the 15 throat 3 of the furnace and the stationary guideway 4 of the rolls are in a line. At this juncture the charging-chute, which is situated a convenient distance in advance of the rolling-mill, is also in position to be lowered at one end and discharge by gravity its 20 contents of metal bars or packs into the mouth of a furnace, which continue to slide down the inclined floor of the furnace to the cross-feedway at the lower end. The inclined floor 25 of the furnace and charging-chute are on the same angle when in operation, said chute being designed to hold the proper number of bars or packs to fill a furnace. When the 30 charging of a furnace is accomplished, said chute is swung up in a horizontal position and beyond contact with the moving furnaces, which, as above described, are progressed until another furnace is brought in the same position, which is charged in a like 35 manner, and so on until all the furnaces in the train are charged. As the last furnace charged moves its length on the circular track the charge of the first furnace has become heated during the progress of said furnace around the circle, and when said furnace has reached the rolling-mill its contents 40 are discharged therein. The circumference of the track and the movement of the furnaces thereon are so timed and bear such relation 45 to each other that in one transit of a furnace around the circular track the time for heating its contents has been accomplished, the charging of one furnace taking place during the discharge of another, and by this means 50 a constant passage of heated metal to the rolls is accomplished, thereby vastly increasing the output or product of a rolling-mill. To release a furnace for progressing in the direction of the arrows, bar 20^a is turned in 55 the bayonet-slot 20^b, so as to let the stop drop out of engagement with the lug 3^a.

The strips or packs are charged at the end 2^a of the furnace, and when ready to deliver to the rolls such packs are ejected from the 60 furnace by means of a pusher inserted in the opening 21, Fig. 2.

22 is a storage table or bench situated a little in advance of the rolls, so that when the charging-chute is empty the packs 23 on 65 said bench are immediately placed thereon, ready from thence to be slid through the

charging-opening (not shown) in the end of the furnace.

25 is a turn-table let into the main track for the purpose of removing any one of the furnaces out of the train for repairs. When such furnace has reached the turn-table, it is uncoupled from the train and the table is turned so as to run said furnace off on either 70 of the spur-tracks 26, 27, and 28 and another 75 furnace, which has been previously heated, is then run into the train to take the place of the one removed.

In Figs. 1 and 8 will be seen means whereby gas and air are conveyed to the tank 10, 80 mounted on the propelling-truck. 29 is a column centrally located with relation to the circular construction of the track. This column is hollow and is supplied with air forced therein through the pipe 30, projecting 85 through the floor. 31 is the gas-pipe, which enters at the side of the column and rises vertically therein. 32 represents lateral holes leading from this pipe into the internal-chambered swivel 33. This swivel loosely embraces the external surface of said pipe and rests against the fixed collar 34, mounted thereon. 35 is a retaining-ring overlying said swivel, between which and said collar the swivel rotates, it being understood that 90 the joints between the said swivel, collar, and rings are properly packed to prevent escape of gas. 36 is a similar swivel mounted on the upper end of the air-column 29 and is provided with the collar 37 and retaining-ring 38. 38^a represents holes similar to holes 32 of the pipe 31, leading from the column into the internal-chambered swivel 36. 39 is the horizontal gas-pipe, radiating from the 95 swivel 33. At its outer free end is connected the depending flexible tube 39^a, attached to the elbow 40 of the tank 10. 41 is the radial air-pipe, having the flexible tube 42, attached to the elbow 43 of said tank, which tank, as before mentioned, is divided 100 into two compartments—viz., one for gas and the other for air.

It will readily be seen that no matter what part of the circular track the truck is on the swiveled connections of the pipes 39 and 41 105 will revolve and always maintain an open communication between the source of supply of gas and air with said tank.

In Figs. 6 and 7 is shown a furnace which has an angular floor 44, with the channel-iron 110 45 mounted thereon. When the metal bars or packs are placed on this inclined floor, they will slide down of their own gravity onto the plate 45^a and from thence be pushed through the throat 3 and into the bight of the rolls. 115

As the time required for emptying a furnace at the rolls is short, it is necessary that the charging of an empty furnace should be done at the same time, so as to avoid delay. For this purpose I employ the chute 46, pivotally mounted by one end to the rod 47. 120 When the furnaces are in motion, the chute

- is elevated by means of the chain 48, connected to its free end, and suitable automatic hoisting mechanism, (not shown,) to a horizontal position, as indicated by dotted lines.
- 5 This elevating feature is necessary to clear the inclined furnaces. While in this horizontal position an operator will load said chute with packs or bars of metal from the table 22, and as soon as a furnace has halted 10 at the rolling-mill for the purpose before stated the free end of the chute is dropped onto the shelf 24 of the furnace to be charged and being of the same inclination or angle as the furnace-floor, as before mentioned, its 15 contents will readily slide into the furnace.

Other means for carrying gas and air to the furnaces than the compound central column and its swiveled radiating arms could be employed. If so desired, the gas might be manufactured on the propelling-truck, or gas alone could be used without the air, or the tank may be dispensed with and direct fuel-gas connections made with the furnaces. Any construction and number of furnaces suitable for convenience and rapid work may also be employed.

From the foregoing description it will readily be seen that the rolling is practically continuous, with but short intermission for advancing the furnaces, which fact is of the utmost importance in the production of large tonnage.

While I show certain means whereby the furnaces are temporarily halted, it will be understood that I do not wish to be confined to the means shown, as other devices may be employed. The charging-chute might also be employed in connection with a stationary furnace, if desired.

40 Having thus described my invention, what I claim as new, and desire to secure by Letters Patent, is—

1. The herein-described system for continuous metal-rolling which consists of an endless track of substantially circular construction, a train of furnaces mounted on wheels and adapted to run on said track, a rolling-mill located in close proximity to said track, for the purpose set forth.

50 2. In a system for continuous metal-rolling, the combination of a rolling-mill located in close proximity to a train of heating-furnaces consecutively arranged in line and adapted to move in fixed and well-defined lines parallel with the rolls of said mill and at right angles to the discharging-line of said furnaces, for the purpose set forth.

3. The herein-described system for continuous metal-rolling which consists of an endless track of substantially circular construction, a train of furnaces adapted to move thereon, a rolling-mill located in close proximity to said track, a turn-table located in said track, for the purpose set forth.

60 4. In a system for continuous metal-rolling, the combination of a rolling-mill located in close proximity with a train of heating-fur-

naces consecutively arranged in line and adapted to move in fixed and well-defined circular lines tangential to the rolls of said mill, for the purpose set forth.

5. In a system for continuous metal-rolling, the combination of an endless track of substantially circular construction, a train of furnaces adapted to run thereon, a propelling-truck, a rolling-mill adjacent to said track, for the purpose set forth.

6. In a system for continuous metal-rolling which consists of an endless track of substantially circular construction, a train of furnaces adapted to run thereon and be supplied with fuel for heating purposes, a rolling-mill adjacent to said track, for the purpose set forth.

7. The herein-described system for continuous metal-rolling which consists of an endless track of substantially circular construction, a train of furnaces adapted to run thereon, a propelling-truck carrying the driving mechanism, and means for supplying fuel-gas, means whereby all the furnaces in the train are supplied with said gas from said truck, a rolling-mill located in the said system and in close proximity to the track, means whereby the furnaces are temporarily halted in position for delivering their contents to said rolls, a turn-table let into said circular track whereby furnaces may be removed from the train and replaced by others, for the purpose set forth.

8. The herein-described system for continuous metal-rolling, which consists of an endless track of substantially circular construction, a train of furnaces adapted to run thereon, a rolling-mill in said system, a section of said track in close proximity to said rolling-mill made substantially straight and parallel with the rolls, of said rolling-mill, for the purpose set forth.

9. In a system for continuous metal-rolling, the combination with an endless track of substantially circular construction, furnaces adapted to move on said track, of a gas-supply within the circular construction of said track to be connected with said furnaces, for the purpose set forth.

10. The herein-described system for continuous metal-rolling, which consists of an endless track of substantially circular construction, a train of furnaces coupled together and adapted to run thereon, a propelling-truck carrying driving mechanism, a gas and air tank or its equivalent thereon, a column or other like device located within the circular construction of said track, means for connecting said column with said truck, swiveled connections whereby the proper relation between the said truck and fuel-supply is at all times maintained, for the purpose set forth.

11. In a system for continuous metal-rolling, the combination with a train of traveling furnaces having inclined floors, of a charging-chute adapted to be loaded with metal preparatory to charging a furnace, means

substantially as shown for an angular connection of said charging-chute with a furnace for discharging its contents therein, for the purpose set forth.

5 12. In a heating-furnace having an inclined floor, the combination of a charging-chute adapted to be loaded with metal preparatory to charging said furnace, means substantially as shown for an angular connection of said charging - chute with said furnace for discharging its contents therein, for the purpose set forth.

13. In a system for continuous metal-rolling, a series of heating-furnaces adapted to 15 be moved in a circular path, combined with a rolling-mill located in close proximity to the line of travel of said furnaces, for the purpose set forth.

14. In a system for continuous metal-rolling, a series of heating-furnaces adapted to 20 be moved in a circular path, a rolling-mill located in close proximity to the line of movement of said furnaces, the circular length of

said path and the speed with which such furnaces travel being such that each furnace is 25 ready to deliver heated metal to the rolls at every revolution about said circular path, for the purpose set forth.

15. The herein-described system for continuous metal-rolling, which consists of an 30 endless track of substantially circular construction, a train of furnaces adapted to run thereon, a column or other like device located within the circular construction of said track, means for connecting said column with said 35 furnaces, swiveled connections whereby the proper relation between said furnaces and fuel-supply is at all times maintained for the purpose set forth.

Signed at Bridgeport, in the county of Fair- 40 field and State of Connecticut, this 3d day of October, A. D. 1900.

THOMAS V. ALLIS.
